UNITED STATES PATENT OFFICE.

JOHN H. MILKS, OF GRAYS RIVER, WASHINGTON.

RAZOR-SHARPENER.

1,107,626.

Specification of Letters Patent. Patented Aug. 18, 1914.

Application filed May 12, 1914. Serial No. 837,994.

To all whom it may concern:

Be it known that I, JOHN H. MILKS, a citizen of the United States, residing at Grays River, in the county of Wahkiakum and State of Washington, have invented certain new and useful Improvements in Razor-
Sharpeners; and I do hereby declare the following to be a full, clear, and exact description of the invention, such as will enable others skilled in the art to which it appertains to make and use the same.

This invention relates to devices for sharpening razors; and it consists in the novel construction and combination of the parts hereinafter fully described and claimed.

In the drawings, Figure 1 is a side view of a razor sharpener constructed according to this invention. Fig. 2 is a plan view of the same. Fig. 3 is an end view of the same. Fig. 4 and Fig. 5 are, respectively, a detail side view and an end view of one of the gages.

A handle 2 is provided, and at the end portions of this handle two tapering plates 3 are arranged. These plates have converging flanges 4 at their side edges which form guides. One plate 3 is secured to the handle in any convenient way, such as by means of a tubular socket 5. A hone 6 of hardened steel, or other approved honing or sharpening material, is provided; and this hone is preferably a bar which is triangular in cross-section.

Metallic clamps 7 are provided for engaging with the end portions of the hone, and the main portions of these clamps are triangular in outline to conform to the shape of the hone. One angle of the hone is arranged to project toward the center of the handle, and flanges 8 are formed at the bottom edges of the clamps and engage slidably with the guide flanges 4 of the plates 3. When the clamps are slid longitudinally of the plates 3 in one direction, the converging guide flanges 4 cause the clamps to contract on the hone so that the hone is rigidly secured to the handle. The hone may be released as often as necessary by sliding the clamps in the reverse direction.

The top plates 10 of the clamps are flat and they rest upon the flat upper surface of the hone and project a little above it, and they have beveled portions 12 at their ends which are nearest to each other. Gages 14 are provided, and are formed right and left

to correspond with the beveled portions 12, but otherwise than being constructed right and left, the clamps and the gages are similar to each other. Each gage 14 has dovetailed side flanges 15 which are slidable on the top portion of the clamp pertaining to it. Each gage has an upwardly projecting gage plate 16 which is inclined diagonally of the hone to a predetermined angle, and each gage has a projecting lug 17 on one side. Each gage is adjustable longitudinally on its clamp, and is provided with a locking device for securing it to the clamp.

Any approved locking device may be used, and in the device shown, a spring 18 is arranged to project from the gage. This spring is retractile, and it has a projection 19 which works in a hole 20 in the top plate of the gage and engages with any one of a series of holes 21 in the top plate of the clamp.

In use the razor is drawn across the hone with its back pressing against one of the projecting gage plates 16. When the gage plate is slid forward, so that it is in line with the beveled end of the clamp, the back of the razor 24 rests on the hone as indicated by dotted lines to the left in Fig. 1. When the gage is moved back, as shown to the right in Fig. 1, the back of the razor rests on the top plate of the clamp, and the angle of the razor blade with the hone is modified. The position of the gage on the clamp is adjusted so as to vary this angle, and enable the edge of the razor to be sharpened or set to the best possible advantage. The top plate 10 of the clamp forms a bearing plate which supports the back of the razor a little above the level of the top of the hone. One plate 3 normally rests on the handle, and the other plate 3, which is secured to the tubular socket 5, has a flanged extension 33 which is tapered in the reverse direction, but which is otherwise similar to the plate 3. If desired, the hone can be turned around so that one clamp engages with the extension 33, and the hone then projects beyond the handle with no support under its free end portion.

What I claim is:

1. In a razor sharpener, the combination, with a hone, of a bearing plate, for the back of the razor, secured to the hone and having a beveled end, and a gage provided with a diagonal gage plate corresponding with the beveled end of the bearing plate, said

gage being adjustable on the bearing plate longitudinally of the hone and provided with means for securing it in place.

2. In a razor sharpener, the combination, 5 with a hone, of a bearing plate, for the back of the razor, said plate projecting above the surface of the hone and having a beveled end, means for clamping the bearing plate to the hone, a gage provided with a diagonal 10 gage plate corresponding with the beveled end of the bearing plate and having dovetailed flanges which are slidable on the bearing plate, and means for securing the gage to the bearing plate.

15 3. In a razor sharpener, the combination, with a handle, and a plate secured thereto and provided with converging side flanges; of a hone, a contractible clamp engaging

with the hone and having base flanges which engage with the said side flanges, said clamp having a bearing plate, for the back of the razor, which projects above the hone and which has a beveled end, and a gage provided with a diagonal gage plate corresponding with the beveled end of the bearing plate, said gage being slidable on the bearing plate longitudinally of the hone and provided with means for securing it in place. 20 25

In testimony whereof I have affixed my 30 signature in the presence of two witnesses.

JOHN H. MILKS.
